SET OF GAME PIECES

Philip Youngman-Carter, 91 Great Russell St.,
London W.C. 1, England

Original design application Feb. 5, 1960, Ser. No. 59,281, now Design Patent No. 192,365, dated Mar. 13, 1962.
Divided and this application Aug. 18, 1961, Ser. No.
66,408

Term of patent 14 years

(Cl. D34—5)

The figure is a view in perspective of a set of game pieces showing my new design.

The essential features of my novel design reside in the portions shown in full lines.

This application is a division of application Serial No. D. 59,281 filed February 5, 1960, now Patent No. D. 192,365, dated March 13, 1962.

I claim:

The ornamental design for a set of game pieces, as shown and described.
